C. G. HAWLEY

METHOD OF HEADING HOLLOW STAY BOLTS

Filed May 13, 1922

Fig. 5.

C. G. Hawley
Inventor

UNITED STATES PATENT OFFICE.

CHARLES GILBERT HAWLEY, OF CHICAGO, ILLINOIS.

METHOD OF HEADING HOLLOW STAY-BOLTS.

Application filed May 13, 1922. Serial No. 560,666.

As is well known, the stay-bolts which are used in staying the flat surfaces of locomotive boilers and the like are threaded into the boiler sheets and after being set therein must be riveted and headed over to make them both secure and steam tight. In recent years approved boiler practices have required the tell-tailing of each stay-bolt, that is, each stay-bolt is required to contain a small central hole long enough to reach considerably beyond the water side of the boiler sheet to the end that if the stay-bolt is fractured, notice of the fracture shall be given by the leakage of steam or water through such tell-tale hole. My invention has to do with the fastening and heading of such stay-bolts, and particularly seeks to encourage the use of so-called hollow stay-bolts, that is, bolts in which the tell-tale holes are formed or drilled before the stay-bolts are placed in the boiler sheets. This has come to be quite a common practice, but under present methods of heading the stay-bolts, is attended by several trying difficulties. The chief difficulty grows out of the fact that in riveting over or heading the tell-tale stay-bolt the metal is upset to such an extent as to close the tell-tale hole, with two annoying results. First, the tell-tale opening must later be bored out, and, more importantly, it is practically impossible to know or be certain that the stay-bolt end has been sufficiently upset or expanded to tightly fit the threads in the boiler sheet, so that the bolt is likely to leak when the boiler is put under pressure and must be re-headed. Other difficulties are recognized, but these will serve to accentuate the importance of the simple invention herein presented.

The particular object of my invention is to lessen the time required to head stay-bolts, and especially to so improve upon the present methods as to insure the tightness of every headed stay-bolt, and further to provide a heading tool especially adapted for use with hollow stay-bolts and which shall serve to keep the tell-tale hole open during the heading operation as contrasted with the usual closing of the tell-tale hole. Other objects of my invention will appear herein-after.

My invention will be readily understood on reference to the accompanying drawings, wherein I have depicted my novel

stay-bolt heading tool, die or bitt and the method of using the same. Fig. 1 of the drawings is a side elevation of my novel heading bitt, the die end thereof being shown in section; Fig. 2 is a section view of a portion of a boiler plate and a stay-bolt screwed into the same ready to be headed; Fig. 3 illustrates the die in operation; Fig. 4 is a separate view showing the boiler sheet with the headed stay-bolt therein; Fig. 5 is an end view of the die or bitt; Figs. 6 and 7 illustrates two modified forms of this novel tool.

It will be understood that the heading tool herein shown is a die stock or bitt designed for use in a pneumatic hammer by which a great number of blows per minute may be struck. In Fig. 1, 2 represents the shank of the bitt and 3 the head thereof. The end 4 constitutes the die surface. This is circular and is slightly dished or cut, the dish generally conforming to a segment of a sphere of from three to four inches in diameter, depending on the size of the stay-bolt to be dealt with. The center of the head 3 is bored out to receive the smaller pin 5, the lower end of which is pointed and will be further described. The shank 2 has a central bore 6, through which a rod may be inserted to dislodge the pin 5 from the head 3, when necessary.

The die face 4 is hardened to withstand the battering which it receives from the resisting heads of the stay-bolts. The center point 5' is usually made of softer and tougher material to offset, as far as possible, the crystallizing effect of the repeated blows which the light point receives in use. Except for this, the long point 5 may be made integral with the head of the die. However, I much prefer to form the pins separately, as they are bound to break more frequently than do the heads or shanks of these bitts. It is convenient to be able to renew the die points.

A common stay-bolt 7 is shown. This is threaded in the opening 8 in the boiler plate 9. The outer end of the stay-bolt projects from $\frac{1}{16}$ th to $\frac{3}{16}$ ths of an inch beyond the plate according to the size of head required on the stay bolt. A $\frac{1}{8}$ th inch projection is here shown and the tool shown is of the size required in heading stay-bolts of one inch diameter.

The stay-bolt contains a tell-tale hole 10,

110

the diameter of which varies; from $\frac{3}{16}$ ths to $\frac{7}{32}$ nds of an inch. This dimension has a direct relation to the size of the point 5'. The point has a ball end 5^a, which is usually $\frac{5}{32}$ nds of an inch in diameter. The shank portion of the point is about one-half inch diameter and the point proper may be either a cone or a diminished cone, that is, one in which the sides are inwardly curved or dished, as clearly shown at 5^b in Figs. 1, 3 and 7. Fig. 6 illustrates a true cone shape. The base of the point gradually enlarges and terminates in a flaring portion 5^c, which merges with the die 15 surface 4 and the perimeter of the pin 5.

The method of using and heading the stay-bolt may be described as follows, it being understood that the die is in place in a pneumatic hammer in the hands of an operator: A stay-bolt being in the condition depicted in Fig. 2, the die is set upon the end thereof with the pin in the stay-bolt hole. Obviously the pin cannot far enter the hole. When the hammer is started into action 25 therefore the pin is driven into the end of the tell-tale hole 10 of the stay-bolt. Meantime, the hammer is oscillated slightly to keep the pin free so that it shall not "freeze" in the bolt. The first effect is to so 30 far expand the end of the stay-bolt as to forcibly set its threads into the threads in the boiler sheet 9. Having reached that condition, the resistance of the sheet to further expansion is such that from that moment forward the action of the hammer is to 35 displace the metal of the stay-bolt outwardly, as here shown upwardly. Comparison of Figs. 2 and 3 discloses that the thickness of the finished head is greater than 40 the initial high part or projection of the stay-bolt shown in Fig. 2. This thickening of the head is brought about by the internal and outward displacement of metal thus described. After an instant's work 45 upon the center of the stay-bolt the operator increases the oscillating or rotating action of the free end of the hammer and thus "rolls" the bitt around the head as depicted in Fig. 3. This action serves two 50 purposes; it flares or increases the size of the outer end 10' of the tell-tale hole, thus doing away with the necessity of later counter-sinking the hole, and, second, the rolling action serves to force the lip 12 of 55 the riveted head into close contact with the surface of the boiler sheet 9. Meantime, the rapidly vibrating pin has served to keep the tell-tale hole open. Obviously, also, the center pin of the die has served to keep the 60 die in central position on the head. Furthermore, during the oscillating or rotating action of the pneumatic hammer, as will be obvious, the center pin will deliver circumferentially progressive hammer blows 65 against the walls of the tell-tale hole, such

blows being necessarily delivered at an angle to the axis and, by reason of the fact that the pin extends within the hole, such blows are delivered below the surface of the plate and simultaneously upon a radially adjacent larger part of the end of the bolt, as will be clearly apparent from Fig. 3. As the operator increases the oscillations of the hammer, the increased angle of the hammer to the axis of the stay bolt will cause the 70 blows to be progressively applied in an outward direction with respect to the bolt, whereby the metal of the bolt is not only forced upward and outward, but the applied pressure due to the hammering action from 75 within the bolt, outward, expands the metal in a direction to set the full length of the threads between the bolt and the plate. 80

When finished, the stay-bolt has much the 85 appearance shown in Fig. 4. The end of the bolt is very slightly expanded and it will be found that its threads are set firmly into the threads of the boiler sheet from inside to outside, virtually precluding the possibility 90 of internal corrosion.

The shape of the finished head may be varied considerably by making very slight changes 95 in the contour of the die surface. For some uses I prefer a die such as shown in Fig. 6, the same presenting a flat annular surface 13 adjacent the end of the center pin. Such a die has the effect of diminishing the thickness of the finished head. For other uses the die surfaces 14 surrounding the center pin may be flat, as shown in Fig. 7. Incidentally Fig. 7 shows that when finished the 100 size of the opening in the stay-bolt is very considerably larger than the size of the center pin of the die.

So far as keeping the tell-tale hole open 105 is concerned, the secret appears to lie in the length of the center pin, which is substantially equal to and usually slightly exceeds twice the diameter of the tell-tale hole to be operated in; and in the ball shaped end 110 of the pin, which avoids the abrasion of the inner walls of the tell-tale hole in the stay-bolt.

Because of the peculiar extruding of the 115 metal by this tool and because of the positive expansion of the stay-bolt end so that it certainly fills the hole in the boiler sheet, I have given to the stay-bolt heads thus formed the name "extruded heads", a term 120 best calculated to distinguish them from the ordinary stay-bolt heads. As proven by the displacement or extrusion of the stay-bolt, it is entirely improper to refer to them as expanded heads. The center expanding of 125 stay-bolts has been attempted in the past, but in every case has proven objectionable because of the enlarging or expansion of the boiler plate and the tendency to crack or check the boiler plate. This is wholly avoided by 130 my invention, wherein the boiler plate is not

disturbed, its holding power being always greater than the resisting power of the stay-bolt metal in the small section or portion whereon the tool acts at any given instant.

5 My preferred form of stay bolt heading tool is not claimed herein as the same forms the subject of a divisional application filed March 28, 1928, Serial #265,466.

Having thus described my invention, I 10 claim as new and desire to secure by Letters Patent:

1. The method of tightening and heading a threaded stay bolt which has a central tell-tale hole and has been screwed into a correspondingly threaded hole in the plate to be stayed and left with its end exposed upon the outer side of said plate, that consists in delivering circumferentially progressive hammer blows against the walls of the tell-tale hole at an angle to the axis thereof and below the surface of said plate and simultaneously on a radially adjacent larger part of the end of the bolt, and during the circumferential progress of such blows progressively increasing the hammer angles with respect to the projected axis of the bolt, by such blows at the end of the bolt, increasing the length of the bolt toward the source of the blows, tightening the threads and 20 forming a spreading head of greater height than the originally exposed end of the bolt.

2. The method of tightening and heading a threaded stay bolt which has a central tell-tale hole and has been screwed into a correspondingly threaded hole in the 35 plate to be stayed and left with its end exposed upon the outer side of said plate, that consists in delivering circumferentially progressive hammer blows against the walls of the tell-tale hole at an angle to the axis 40 thereof and below the surface of said plate and simultaneously on a radially adjacent larger part of the end of the bolt, and during the circumferential progress of such blows progressively increasing the hammer 45 angles with respect to the projected axis of the bolt causing the metal of the wall of the tell-tale opening below the surface of the plate to be extruded outwardly to enlarge the head and at the same time causing the 50 metal of the bolt to be forced towards the screw threads to tighten the same; by such blows at the end of the bolt, increasing the length of the bolt toward the source of the 55 blows, and forming a spreading head of greater height than the originally exposed end of the bolt, and finally so increasing the hammer angle as to circularly trim the edge of the head against the plate.

In testimony whereof, I have hereunto set 60 my hand this 6th day of May, 1922.

CHARLES GILBERT HAWLEY.
